UNITED STATES PATENT OFFICE.

D'ORSAY McCALL WHITE, OF DETROIT, MICHIGAN.

INTERNAL-COMBUSTION ENGINE.

Application filed December 10, 1923. Serial No. 679,617.

This invention relates to internal combustion engines and has for its object a special form of improved drive for the generator and valve operating shaft. It is customary to connect these shafts, ordinarily at the front of the motor, by either gears or what is known as a silent chain. The so-called timing gears have given rise to a great many difficulties. When economically and cheaply made they soon wear and give forth objectionable humming noises. In order to avoid these troubles, fiber gears and gears made of other composition materials have been introduced with more or less 15 different success. Chains have been quite successful but if not properly adjusted they too are noisy and troublesome and they require considerable attention and at times give considerable trouble. Furthermore, if 20 one of the operative units, such as the generator, has to be removed from the motor, then ordinarily the entire front of the car has to be torn down in order to remove the cover of the chain housing and permit the 25 generator shaft to be drawn out of the sprocket.

It is the object of the present invention to supplant the ordinary timing gears or chain drive with an eccentric drive frame. 30 This form of drive under ordinary conditions and with proper lubrication is absolutely noiseless. It has the additional feature of permitting one of the shafts to be removed without requiring the housing 35 cover to be removed for the eccentric frame when designed for driving three shafts has the capacity of supporting itself in proper relation when only one shaft is removed. This is especially desirable in connection 40 with the generator which is quite frequently removed from care for repairs and renewals.

Another feature of my invention having a direct relation with this form of eccentric 45 frame is the valve operating mechanism. I preferably employ a sleeve valve of the Argyll type. Instead of driving the operating shaft at one half crank shaft speed, I drive the same at crank shaft speed and secure my speed reduction in the driving elements between the operating shaft and the sleeves. This permits the direct coupling 50 of the crank shaft and the generator shaft and the valve operating shaft by such a driving unit as an eccentric frame—a form

of transmission which does not permit a speed variation.

In the drawings:

Fig. 1 is a front elevation of the driving connections between the crank shaft, valve-operating shaft and generator shaft—accurately, this is a section taken on the line 1—1 of Fig. 2.

Fig. 2 is a section taken on the line 2—2 of Fig. 1.

Fig. 3 is a section taken on the line 3—3 of Fig. 1 showing part of the generator and generator shaft.

Fig. 4 is a fragmentary longitudinal section taken on the line 4—4 of Fig. 1.

Fig. 5 is a section taken on the line 5—5 of Fig. 4.

a designates the engine block casting, *b* the housing at the front of the motor that ordinarily houses the chain or the timing gears. Referring to Fig. 5, *c* represents the reciprocating and turning "Argyll" sleeve; *d* designates the piston. This port-controlling sleeve *c* is driven in its path by means of a crank pin *e* which is provided with a ball joint *f* with the sleeve. This crank pin is part of a forging on which are cut the helical gear teeth *g*. These are arranged to engage the helical gear teeth *h* on the valve operating shaft *i*. The gear ratio here is a 2 to 1 reduction in the valve operating shaft to the valve operating crank. This gets the proper driving relation for the sleeve in view of the fact that the valve operating shaft is operated at crank shaft speed.

Now referring to Fig. 1, it will be seen that the valve-operating shaft *i* is keyed to an eccentric *i'*. On the left hand side of the motor the generator shaft *j* is keyed to an eccentric *j'*. The crank shaft *k* is keyed to the eccentric *k'*. A triangular frame *m* can be bolted to the three eccentrics *i'*, *j'*, and *k'* by the caps *i²*, *j²* and *k²*. In the drawings it has been thought unnecessary to show any ball or roller bearings between the eccentrics and the frame but obviously these could be used if the friction is so great as to make these desirable.

Referring to Fig. 2, it will be seen that counter-weights 100 are provided on the ends of the shafts. These counter-weights are intended to substantially balance what would be the otherwise unbalanced forces set up by the excess mass of the eccentric at one side of the center. By interposing these 110

counter-weights with the counter-weight mass directly opposite the large mass of the eccentric, the eccentric has substantially a running balance as well as a static balance. The same keys that key the shaft to the eccentric, key the shaft to the counter-balance, the counter-balance being preferably carried on the independent disc σ . The eccentric as shown is provided with bushings p which may be slipped on before the counterbalancing disc is slipped on to the shaft.

The valve-operating shaft i is provided with an extension which passes to the outside of the drive housing q . On the end of this extension is mounted the fan pulley wheel r , the hub of the pulley wheel being keyed to the end of the shaft and all the parts held together by the castellated nut s .

Turning to Fig. 3 it will be seen that the generator t can be detachably bolted to the drive housing q by means of the cap screws u . By taking out the screw plug v in the front of the housing a shaft nut w is accessible with a wrench for the wrench hold of this long nut is at the outside of the housing when the screw plug is removed. When this nut and the spring washer x are removed, the generator t may be pulled directly out of the eccentric as the generator shaft y simply has a sliding key connection with the eccentric. The counter-weight disc σ may be secured to the eccentric by machine screws z or in any other way so that when the shaft is removed it will not drop off. This form of triangular eccentric frame

drive for the crank shaft, the generator shaft and one other shaft, has a great ad-

vantage in connection with the generator shaft. It permits the generator shaft to be drawn out of the driving mechanism without in any way displacing the driving mechanism for the reason that the triangular eccentric frame is supported at two other points by the two other shafts and consequently will not be displaced when the generator shaft is drawn out. This is not true with the ordinary form of chain drive for here ordinarily the cover of the chain housing has to be removed and the chain taken out before the generator shaft can be withdrawn. However, in a co-pending application Serial No. 679,618 I have described and claimed an assembly provided with a suitable support for the sprocket when the generator shaft is withdrawn. But by using the triangular form of frame and the eccentric drive, no such support is required.

What I claim is:

In an internal combustion engine, the combination of a driving housing, a valve-operating shaft, a crank shaft and a generator shaft projecting into the driving housing, eccentrics on each of the shafts and contained within the housing and an eccentric frame connecting said three shafts in driving relation, the generator shaft having a sliding connection with the eccentric, whereby it is permitted to withdraw the generator from the companion eccentric which will be supported by the eccentric frame.

In testimony whereof I affix my signature.

D'ORSAY McCALL WHITE.
